UNITED STATES PATENT OFFICE.

HARRY WARD, OF PETOSKY, MICHIGAN.

DESIGN FOR A WIRE FENCE.

No. 37,611.

Specification for Design.

Patented Oct. 31, 1905.

Application filed April 22, 1905. Serial No. 257,002. Term of patent 14 years.

To all whom it may concern:

Be it known that I, HARRY WARD, a citizen of the United States, residing at Petosky, in the county of Emmett, State of Michigan, have invented a new, original, and ornamental Design for a Wire Fence, of which the following is a specification, reference being had to the accompanying drawing, forming part thereof.

The figure is an elevation of a portion of a wire fence, showing my new design.

I claim—

The ornamental design for a wire fence, as shown.

HARRY WARD.

Witnesses:

CHARLES A. STYER,
JAMES C. BLACKLIDGE.
